APPARATUS FOR STOWING ROCK IN A
COAL MINE

Frank Cartlidge, Chicago, Ill., assignor to Goodman Manufacturing Company, Chicago, Ill., a corporation of Illinois

Application November 18, 1938, Serial No. 241,101

5 Claims. (Cl. 198—7)

This invention relates to improvements in apparatus for stowing rock in a coal mine and more particularly relates to improvements in a mobile conveying apparatus adapted to receive material from a loading machine and stow this material in a low portion of the working place.

In driving entries in thin coal seams, it has heretofore been the practice to drive the entry for its full width and either shoot down the rock from the top of the central part of the entry or take up rock from the bottom to increase the working height of the entry. Due to the prohibitive cost of removing this rock from the mine, it is usually stowed or gobbed in the low portion of the entry by hand at a considerable expenditure of time and money. The use of conveyors to stow this rock has never been satisfactory, especially where the roof must be held up by props, for the reason that the loading machine must continually move back and forth along the track to pick up the rock from the floor, and it has been difficult to get the stowing conveyor to discharge between the props and still arrange it so that material may be continuously discharged from the loading machine onto the stowing conveyor during movement of the loading machine along the track.

A prior application filed by Thomas E. Pray on November 12, 1938, Serial No. 239,902, illustrates and describes an apparatus for stowing rock in mines. The device of my present invention, however, differs from that shown in the Pray application in that the gobbing apparatus is arranged to remain stationary on the track during the stowing operation instead of being movable with the machine.

The principal object of my invention is to provide an apparatus for stowing or gobbing rock in a coal mine, of a new and improved construction including a novel arrangement of conveyors, one of which is adapted to be disposed beneath the discharge end of the discharge conveyor and receive material discharged thereby as the loading machine moves towards and from the apparatus while picking up loose material from the ground, and another of which is arranged to discharge and distribute rock in a gobbing area in the mine to one side of the apparatus.

Another object of my invention is to arrange the discharge conveyor of the loading machine and receiving conveyor of the gobbing apparatus in such a manner that said discharge conveyor may continuously discharge material into said receiving conveyor when said discharge conveyor is moving towards and from said receiving

conveyer including a guiding connection between said conveyers whereby said discharge conveyor may be guided to travel along said receiving conveyor, and may swing said receiving conveyor as said discharge conveyor is swung from side to side.

Other objects of my invention will appear from time to time as the accompanying specification proceeds.

My invention will be more clearly understood with reference to the accompanying drawings wherein:

Figure 1 is a view in side elevation of a loading machine mounted on a track, with a gobbing apparatus constructed in accordance with my invention coupled thereto, for tramping about a mine from one working place to another;

Figure 2 is an enlarged plan view of the rear part of the loading machine arranged to discharge material into the gobbing apparatus, showing the apparatus in a mine entry in position to discharge material in the low portion of the entry;

Figure 3 is an enlarged plan view of the gobbing apparatus, showing the gobbing conveyor disposed at right angles with respect to the receiving conveyor, and showing certain parts of the apparatus broken away and in section;

Figure 4 is a view in side elevation of the gobbing apparatus drawn to a slightly larger scale than Figure 3, with certain parts shown in substantially longitudinal section and with the gobbing conveyor shown as being disposed at right angles with respect to the receiving conveyor;

Figure 5 is a view in side elevation of the rear part of the gobbing apparatus with certain parts shown in substantially longitudinal section and showing the gobbing conveyor arranged in alignment with its supporting truck;

Figure 6 is an enlarged detail view of the rear end of the discharge conveyor of the loading machine showing certain details of the guiding connection between the discharge conveyor of the loading machine and receiving conveyor of the gobbing apparatus; and

Figure 7 is an enlarged fragmentary sectional view taken substantially along line 7—7 of Figure 2.

Like reference characters refer to like parts throughout the several figures.

The embodiment of my invention illustrated in the drawings is shown with a loading machine 10, which is herein shown as being a track mounted loading machine of a usual construction including a gathering element and elevating con-

veyer 11 projecting forwardly from the supporting truck for the machine, for picking up loose material from the ground and discharging it into a discharge conveyer 12 extending rearwardly beyond the rear end of the machine. Said discharge conveyer is mounted for vertical adjustment and for horizontal swinging movement to permit the discharge of material to either side of the track, or into cars when the machine is 10 loading around a curve.

A gobbing apparatus 13 is herein shown as being disposed beneath the discharge end of the discharge conveyer 12 of the loading machine and includes a receiving conveyer 14 mounted 15 on and extending longitudinally along a track mounted truck 15 and adapted to be overhung by said discharge conveyer, and of a length equal substantially to the length of the path of travel of the loading machine along the track during 20 gobbing, and a stowing or gobbing conveyer 20 supported by the rear end of said receiving conveyer in cascade relationship with respect thereto. A suitable coupling member 16 may be provided to couple the truck 15 with the loading machine when it is desired to transport the apparatus about the mine.

The truck 15 has a projecting frame portion 17 which extends beyond the track wheels and axles which are disposed adjacent the loading machine, in a direction towards the loading machine, which direction will hereinafter be termed a forward direction. Said projecting portion of said truck forms a pivotal support for the forward end of the receiving conveyer 14 (see Figure 4).

The receiving conveyer 14 is pivotally mounted at its receiving or forward end on the forwardly projecting portion 17 of the truck 15 on a shouldered bearing member 23. Said shouldered bearing member is secured at its top to a bottom 24 of a frame 25 for said receiving conveyer in a suitable manner, such as welding, and extends through and has bearing engagement with an aperture formed in a cross member 26 of the forward frame portion 17 of said truck. A shaft 27 is mounted in and extends through said bearing member and depends therefrom. Said shaft is mounted at its lower end in a cross member 28 of said forward frame portion.

The rear end of the receiving conveyer 14 is supported on a track 30, herein shown as being of an arcuate formation conforming to the arc of swinging movement of said receiving conveyer. Said track is secured to the rear end of the truck 15 and extends laterally beyond opposite sides thereof. A plurality of rollers 31, 31, mounted in a depending bracket 18, are provided to support said conveyer on said track.

The bracket 18 depending from the rearward end of the receiving conveyer 14 has a rearwardly extending substantially horizontally disposed gear housing and supporting frame member 19 extending therefrom which forms a pivotal support for the gobbing conveyer 20 (see Figure 5). Said gear housing and supporting frame member, besides forming a support for said gobbing conveyer for supporting said conveyer for movement about a vertical axis, also forms a housing and bearing support for the gearing for driving and swinging said gobbing conveyer about its axis of pivotal connection to said support, in a manner which will hereinafter more clearly appear as this specification proceeds.

The receiving conveyer 14, as herein shown, 75 is a flight conveyer of an ordinary construction

and includes a pair of spaced apart endless chains 33, 33 having a plurality of parallel spaced flights 34, 34 mounted therebetween. Said endless chains are trained around idlers 35, 35 at the forward end of the conveyer frame 25 and extend along a plate 36. Said plate forms a bottom for the conveyer, along which the loose material is carried, and is mounted between upwardly extending and outwardly flared side walls 37, 37 of the frame 25. Said chains are thence trained around idlers 38, 38 at the rear of the conveyer and forwardly along the bottom plate 24 of the conveyer over suitable drive sprockets 39, 39 on a transverse shaft 40, and under tension idlers 41, 41 to and around the idlers 35, 35.

The gobbing conveyer 20 is mounted on a support member 44, which support member is in turn mounted on and secured to the upper end of a vertical shaft 45 (see Figure 5). Said vertical shaft is journaled in the gear housing and supporting frame member 19 intermediate its ends and has a worm gear 46 secured to its lower end which worm gear is enclosed by the gear housing and supporting frame member 19, and is journaled on its hub in the lower portion of said housing. Said worm gear forms a means for pivotally moving said shaft and swinging said gobbing conveyer in a horizontal plane, and is meshed with and driven from a worm 47 on a transverse shaft 48. Said worm and worm gear are of the self-locking type, to lock said gobbing conveyer in various positions of adjustment with respect to said receiving conveyer, and said worm is driven through a chain and sprocket drive 49 and a bevel gear 50 adapted to be meshed with and driven from either one of a pair of facing bevel gears 51, 51 on a shaft 53. A pair of clutches 54, 54, herein shown as being of the friction cone type, is provided to selectively connect said bevel gears with said shaft for driving the bevel gear 50, and swinging said gobbing conveyer in reverse directions without reversal of said shaft. The details of the drive to said shaft will hereinafter more clearly appear as this specification proceeds.

The gobbing conveyer 20 is likewise shown as being a flight conveyer of an ordinary construction and includes a pair of spaced apart endless chains 56, 56 having flights 57, 57 carried therebetween. Said endless chains are trained around idlers 59, 59 mounted at the front end of the frame for said conveyer and extend rearwardly and upwardly along a bottom plate 60 mounted between side frame members 61, 61 of the conveyer frame.

The side frame members 61, 61 are outwardly flared at their upper edges, and are connected together at their forward ends by a flared inclined plate 63. Said side frame members together with the plate 63 may thus form a hopper, disposed beneath the discharge end of the receiving conveyer 14 for collecting material discharged therefrom.

The endless chains 56, 56 extend along the bottom plate 60 in a rearward and upwardly inclined direction and are trained around idlers 64, 64 at the rear end of said gobbing conveyer frame. From said idlers, said chains extend forwardly and downwardly over drive sprockets 65, 65 and tension idlers 66, 66 to and around the 70 idlers 59, 59.

With reference now in particular to the power drive connections to the conveyers 14 and 20 and the power drive connection for independently swinging the conveyer 20 in a horizontal 75

direction, a motor 55 is mounted in the forwardly projecting portion 17 of the truck 15. A bevel gear 69 is mounted on a transverse shaft 70, journaled at the forward end of the forwardly projecting portion 17 of the truck 15. Said bevel gear is driven from said motor by means of a chain and sprocket drive generally indicated by reference character 71 (see Figures 3 and 4). Said bevel gear meshes with a bevel gear 72 10 journaled on the vertical shaft 27. Said last mentioned bevel gear meshes with and drives a bevel gear 74 on the forward end of a longitudinally extending shaft 75. Said longitudinal shaft is journaled at its forward end and intermediate its ends in bearing brackets 76, 76 secured to and depending from the bottom 24 of the conveyer frame 25 and is journaled in the bracket 18 at its rear end. The shaft 75 may thus swing upon swinging movement of the receiving conveyer 14 and be driven from the motor 55 in the various positions of adjustment of said receiving conveyer with the truck 15, provision being made in the frame for the truck 15 to permit swinging movement of said shaft 25 and conveyer frame with respect to said truck.

The drive to the conveyer 14 includes a bevel gear 79 secured to the shaft 75 intermediate the ends thereof, which meshes with and drives a bevel gear 80 on the inner end of a transversely extending shaft 81, for driving said shaft (see Figure 3). The transverse shaft 40 is driven from said last mentioned shaft for driving the drive sprockets 39, 39 by means of a chain and sprocket drive generally indicated by reference character 82.

The conveyer 20 is swung about the axis of the shaft 45 and driven from the rear end of the shaft 75 by means of a spur pinion 83, secured to the rear end of said shaft and meshing with a spur gear 84, secured to the forward end of the shaft 53 for driving said shaft (see Figure 5). The gobbing conveyer 20 may thus be swung by power in reverse directions without reversal of the motor 55, through the clutches 54, 54 and bevel gears 51, 51 and 50 when the receiving conveyer 14 is in various positions of adjustment with respect to the truck 15.

The gobbing conveyer 20 is driven from the end of the shaft 53 opposite from the spur gear 84 by means of a bevel gear 85 which meshes with a bevel gear 86 journaled on the vertical shaft 45. Said bevel gear meshes with and drives a bevel gear 87 secured to the end of a horizontal shaft 88, journaled in the support member 44. A bevel gear 89 is secured to the rear end of said shaft and meshes with and drives a bevel gear 90 on a transverse shaft 91. Said transverse shaft has driving connection with the drive sprockets 65, 65 for driving said sprockets by means of a chain and sprocket drive generally indicated by reference character 92.

It may be seen from the foregoing that the motor 55, mounted on the truck 15, serves to drive both the receiving and discharge conveyers when said conveyers are in various positions of adjustment with respect to each other and with respect to the truck 15, and also serves to independently swing the gobbing conveyer in reverse directions without reversal of said motor. This permits the gobbing conveyer to be swung by power to and fro about its axis of pivotal connection to the housing and supporting frame 19 and distribute material between the props without interrupting the drive to both conveyers.

A novel form of guiding connection is provided between the discharge conveyer 12 and receiving conveyer 14 for guiding said discharge conveyor for movement along said receiving conveyor to permit the discharge of material into said receiving conveyer when the loading machine is moving back and forth along the track towards and from said receiving conveyer, and to swing said receiving conveyer upon swinging movement of said discharge conveyer. Said 10 guiding connection includes a pair of brackets 93, 94 secured to and projecting outwardly from and depending from opposite sides of said discharge conveyer (see Figures 2, 6, and 7). Each of said brackets has a pin 95 mounted therein, 15 to which is pivotally connected the upper end of a depending and outwardly extending guide member 96. Said guide members, as herein shown, extend outwardly and downwardly from the pins 95, 95 and are provided with depending ends which are adapted to slidably engage opposite sides of the receiving conveyer 14, thus forming a guiding connection between said discharge and receiving conveyers, to permit the discharge of material from said discharge conveyer into said receiving conveyer as said discharge conveyer moves along said receiving conveyer, and also forming a means for swinging said receiving conveyer about its axis of pivotal connection to the truck 15 upon swinging movement of said discharge conveyer in an obvious manner. Said discharge conveyer may thus serve as a means to extend the gobbing conveyer 20 into, or withdraw it from the gobbing area and also to permit the discharge of material from the discharge to receiving conveyer when the loading machine is operating around a curve.

In operation, the gobbing apparatus may be coupled to the loading machine by means of the coupling member 16 and be transported into the entry by means of said loading machine. When the gobbing apparatus is in the proper location, said coupling member may be disconnected, to permit movement of the loading machine with respect to the gobbing apparatus towards and from the working face, for picking up the loose material from the ground while said gobbing apparatus remains stationary on the track. The guide members 96, 96 may then be engaged with the outer sides of the receiving conveyer 14 and said receiving conveyer may be swung in a direction away from the side of the entry that it is desired to insert the gobbing conveyer 20, while said gobbing conveyer is swung about the axis of the vertical shaft 45, so it may readily be inserted between the props to discharge material close to the rib, with the removal of a minimum number of props. When the gobbing conveyer has been inserted between the props the loading machine may then pick up the rock from the working place and discharge it into the receiving conveyer 14 and thence into the gobbing area by means of the gobbing conveyer 20. Said gobbing conveyer may be swung back and forth about the axis of the shaft 45 to distribute its load in the gobbing area and when desired may also be swung towards or from the rib about the axis of connection of the conveyer 14 to the truck 15 by swinging movement of the discharge conveyer 12, through the guiding connection between said discharge and receiving conveyers.

It may thus be seen that a novel form of gobbing apparatus has been provided which is adapted to be in a stationary position during the gob-

bing operation and continuously receive material discharged from the discharge end of a loading machine while said loading machine travels backwardly and forwardly along the track for picking up the loose material, thus making the gobbing operation a substantially continuous operation.

It may likewise be seen that the gobbing apparatus includes a pair of conveyers, one of which is pivotally mounted to the forward end of its supporting truck and extends rearwardly therealong beyond the rear end thereof, and has the other supported by and pivotally connected to its discharge end; that said conveyers are driven from a single source of power; that the gobbing conveyer may be reversely swung by power during the gobbing operation; and that the discharge conveyer of the loading machine may swing the gobbing and receiving conveyers about the axis of pivotal connection of the receiving conveyer to its supporting truck for moving the gobbing conveyer inwardly or outwardly with respect to the rib of the entry and to permit continuous loading from said discharge conveyer to said receiving conveyer when the loading machine is operating around a curve.

While I have herein shown and described one form in which my invention may be embodied, it will be understood that the construction thereof and the arrangement of the various parts may be altered without departing from the spirit and scope thereof. Furthermore, I do not wish to be construed as limiting myself to the specific embodiment illustrated, excepting as it may be limited in the appended claims.

I claim as my invention:

1. In a gobbing apparatus and in combination with a loading machine having a rearwardly projecting discharge conveyer, a truck having a receiving conveyer mounted thereon for movement about a vertical axis adjacent the forward end thereof and extending along said truck beyond the rearward end thereof, a guiding connection between said discharge and receiving conveyers for guiding said discharge conveyer for movement along said receiving conveyer to permit discharge of material from said discharge to receiving conveyers upon back and forth movement of said loading machine with respect to said truck during the gathering operation and for pivotally moving said receiving conveyer about its axis of pivotal connection to said truck upon swinging movement of said discharge conveyer, and a gobbing conveyer adapted to stow rock laterally beyond the side of said truck, said conveyer being arranged in cascade relationship with respect to said receiving conveyer and being supported by said receiving conveyer for pivotal movement about a vertical axis rearwardly of the rear end of said receiving conveyer, to permit the positioning of said conveyer between the props in the working place and the distribution of rock in the gobbing area.

2. In a gobbing apparatus and in combination with a track mounted loading machine having a horizontally swingable rearwardly projecting discharge conveyer, a track mounted truck adapted to be disposed beneath said loading machine and remain stationary on the track during backward and forward movement of said loading machine along the track, a receiving conveyer of a greater length than the length of the path of travel of said loading machine along the track during the gathering operation, said conveyer being mounted for movement about a vertical axis disposed

adjacent the forward end of said truck and extending along said truck beyond the rear end thereof, a guiding connection between said discharge and receiving conveyers to guide said discharge conveyer for movement along said receiving conveyer to discharge material into said receiving conveyer during movement of said loading machine back and forth along the track while picking up material, and a gobbing conveyer arranged in cascade relationship with respect to the discharge end of said receiving conveyer and mounted for swinging movement about a vertical axis disposed rearwardly of said truck, to permit the positioning of said conveyer between the props in the working place and the distribution of rock in the gobbing area.

3. In a gobbing apparatus and in combination with a track mounted loading machine having a horizontally swingable rearwardly projecting discharge conveyer, a track mounted truck adapted to be disposed beneath said loading machine and remain stationary on the track during backward and forward movement of said loading machine along the track while gathering loose material from the ground, a receiving conveyer extending along said truck beyond the forward and rearward ends thereof and mounted thereon for movement about a vertical axis disposed adjacent its forward end, a guiding connection between said discharge and receiving conveyers for guiding said discharge conveyer for movement along said receiving conveyer for discharging material into said receiving conveyer upon movement of said loading machine back and forth along the track during the gathering operation and for pivotally moving said receiving conveyer about its axis of pivotal connection to said truck upon swinging movement of said discharge conveyer, and a gobbing conveyer arranged in cascade relationship with respect to said receiving conveyer and pivotally supported thereby for movement about a vertical axis, to permit the positioning of said conveyer between the props in the working place and the distribution of rock in the gobbing area.

4. In a gobbing apparatus and in combination with a track mounted loading machine having an overhanging horizontally swingable discharge conveyer, a truck frame mounted on track wheels and axles and having a portion projecting forwardly beyond the front truck wheels, a receiving conveyer pivotally mounted on the forwardly projecting portion of said frame for movement about a vertical axis, said conveyer extending along said frame and rearwardly beyond the rear end thereof, a gobbing conveyer arranged in cascade relationship with respect to said receiving conveyer and pivotally supported by said receiving conveyer for movement about a vertical axis disposed beyond the discharge end of said receiving conveyer, and a sliding guiding connection between said discharge and receiving conveyers to permit said discharge conveyer to move along said receiving conveyer and discharge material therein as said loading machine is moving towards and from said receiving conveyer.

5. In a gobbing apparatus and in combination with a track mounted loading machine having an overhanging horizontally swingable discharge conveyer, a truck frame mounted on track wheels and axles and having a portion projecting forwardly beyond the front truck wheels, a receiving conveyer pivotally mounted on the forwardly projecting portion of said frame for movement about a vertical axis, said conveyer extending along said frame and rearwardly beyond the

rear end thereof and having slidable supporting engagement with said frame adjacent the rear end thereof, a gobbing conveyer arranged in cascade relationship with respect to said receiving conveyer and pivotally supported by said receiving conveyer for pivotal movement about a vertical axis disposed rearwardly of the rear end thereof, a power drive connection for swinging said gobbing conveyer about said vertical axis,

and means for swinging said receiving and gobbing conveyers about the axis of pivotal connection of said receiving conveyer to said truck upon swinging movement of said discharge conveyer about its axis of pivotal connection to the loading machine including a slidable guiding connection between said discharge conveyer and the sides of said receiving conveyer.
